IGNITER TORCH

Edward D. Wilson, Newport, Ore.

Application November 16, 1938, Serial No. 248,698

6 Claims. (Cl. 67—20.1)

This invention relates to a self lighting torch of the type used for soldering, light brazing and general construction work in manufacturing and repair shops.

Such torches are operated by gas, usually acetylene gas mixed with air, the mixing being done by a siphon built into the torch behind the flame tube or nozzle, with a main cut-off valve and a modulating valve to regulate the mixture. Lighting such a torch requires enriching the mixture because it is lighted at the tip of the flame tube. More air has been mixed with the gas as it leaves the tube and it is too lean to ignite readily. Enriching the mixture connotes opening the modulating valve, thus disturbing its optimum adjustment, then getting it back, which consumes the workman's time and some extra gas.

An object, therefore, is a torch that ignites instantly when the gas is turned on by the cut-off valve, without adjustment of the gas-air mixture, which improves the known art as above stated.

The foregoing and other objects which will be apparent, constitute the purposes of the present invention, the scope of which is to be ascertained by the claims following this specification.

A drawing showing the best form with which I am now acquainted, forms a part hereof and serves to illustrate the invention and also is keyed to the specification by reference numerals indicating the several parts therein described.

In the drawing:

Fig. I is a side view, partly sectioned, showing the torch with ignition device, while the same is in position of use, the arrow representing sustained pressure by the operator's finger;

Fig. II is the same structure shown in Fig. I except that the pressure has been relaxed, the torch automatically becoming dormant; and

Fig. III is a section at III—III, Fig. I.

In the drawing, 1 is the flash-back protector, not detailed because it is well known, here serving also as a handle for the torch.

2 is a modulating valve, likewise well known. 3 is a main cut-off valve always used but in this case it is normally closed under the influence of the spring 4 that acts against the trigger 5, which in turn is made rigid with the ground key 6, not further detailed because it is old and well known.

The valve 3 serves as a supporting element for the mixing tube 8 which is provided with the usual air inlet openings 9. The mixing tube 8 serves in turn as a support for the flame tube

10. As so far described and ignoring the structure shown but not yet referred to, the device does not differ in any essential particular from the torches used in great numbers in industry, but I have added to the old art as follows:

I provide a side outlet 11 in the flame tube 10 and a movable sleeve 12 that covers the opening thus made. The sleeve 12 carries a flint holder 13 within which is the spring 14 and the flint 15. The word "flint" is conventional and does not refer to the geologic material known as flint but to an article of commerce, widely used in cigar and cigarette lighters and known as "flint"; hence the word will be used to designate a material that gives a spark when struck against steel.

The flint 15 is kept in resilient contact with the steel 16, by the spring 14. I have found that a short piece of a rat-tail file serves admirably as the steel when it is laid in the flame tube 10 loosely, as shown.

As stated, the sleeve 12 is movable and it is indirectly connected to the trigger 5 by the reachrod 17 and the compression spring 18. A detent spring 19 serves to prevent too quick a movement of the flint against the steel 16, when the trigger 5 is pressed and before gas is present to be ignited.

When the trigger 5 is pressed, moving it from the position shown in Fig. II to that shown in Fig. I, the spring 18 is first compressed and the detent 19 prevents any movement of the sleeve 12 before the ports in the shut-off valve (not shown) have registered to pass gas to the mixing tube 8 and the flame tube 10.

When the spring 18 has all of its coils together as happens when the trigger 5 is pulled nearly as far back as it will go, the resistance of the detent 19 is overcome and it slides up on top of the sleeve 12 as shown in Fig. I, where it offers little resistance to sliding of the sleeve 12; hence the latter rapidly slides back under the influence of the spring 18, the flint 15 has an ideally rapid frictional contact with the steel 16 producing a strong spark and at the same time the tip of the flame tube 10 is exposed for work.

It will be observed that the spark lights the working mixture which is easily ignitable and the modulating valve may be set to its optimum position and not afterwards disturbed.

When a workman desires to use the torch he picks it up, squeezes the trigger and finds an optimum flame instantly available for his work. Should he lay the torch down or drop it accidentally, it instantly resumes its dormant, un-

lighted condition; hence accidents are prevented and time is saved, besides improving work done with the tool in its best possible adjustment at all times.

5. The detailed description given the preferred form is for the purpose of explaining the principle of its operation and not intended as limiting the invention to the form selected for its disclosure. What I claim as new and desire to secure by Letters Patent is:

1. A torch igniter comprising a gas torch member, a flame tube for said torch member that is provided with a side opening, a movable sleeve that covers the side opening, friction ignition means carried in part by said sleeve to project through said side opening and a cooperating part of said ignition means positioned within the flame tube, and detent and spring means for moving the said sleeve abruptly with respect to 20 the tube to generate a spark within the tube.

2. In a gas torch, a flame tube, a normally closed gas control valve therefor, an air supply that becomes operative upon flow of gas, a spark igniter positioned within the tube, a lever for opening said control valve, operative connections between the lever and the igniter effective to cause the igniter to deliver a spark after the control valve has been opened and a spring opposed lost motion device in series in said operative connections.

3. In a gas torch, a flame tube, a normally closed control valve for said tube, a gas air mixer, a lever for manually opening the valve, a flint and steel igniter positioned within the flame tube, a connector joining the said lever and the igniter and spring means in series between said lever

and said igniter arranged to first yield upon movement of said lever and afterwards to cause an abrupt movement of the igniter upon further movement of the lever.

4. A flame tube for a gas torch that is provided with a side outlet, a steel within the tube adjacent the outlet, a slideable sleeve over the outlet a flint projecting through the outlet and carried by said sleeve in resilient engagement with the steel an operating rod for said sleeve, a spring 10 in series with said rod and a detent yieldably positioned to hold said sleeve until overcome by resilient action of said spring.

5. In a torch of the character described, a flame tube, an igniter therein, a gas control valve 15 for said flame tube having an operating lever a sleeve slidably mounted on the flame tube that is effective to operate the igniter, a detent therefor and means yieldably connecting said sleeve to said operating lever said operating lever actuating both the sleeve and the gas control valve means, said detent positioned to prevent the sleeve from moving until the lever has moved to gas supplying position.

6. In a gas torch, a flame tube, gas supply 25 means operatively connected to said tube, a modulating valve and a shut-off valve in series in said supply means and a spark igniter positioned within the flame tube near its operating end, an operating trigger for the shut-off valve, an operator connector between said trigger and said igniter and means interposed in series in the operator connector effective to delay operation of the igniter until after the shut-off valve has 30 35 opened.

EDWARD D. WILSON.
